UNITED STATES PATENT OFFICE.

WALTER HOLUB, OF LA SALLE, ILLINOIS.

SHOE-STRETCHER.

1,307,778.

Specification of Letters Patent. Patented June 24, 1919.

Application filed December 5, 1917. Serial No. 205,532.

To all whom it may concern:

Be it known that I, WALTER HOLUB, a subject of the Republic of Russia, residing in the city of La Salle, county of La Salle, and 5 State of Illinois, have invented certain new and useful Improvements in Shoe-Stretchers, of which the following is a specification.

My invention relates to shoe-stretchers and has for its object the production of a device 10 by which it is possible by the same actuating means to spread as well as lengthen shoes and giving them various shapes such as to conform to the shape of the feet.

I accomplish this by means shown in the 15 accompanying drawing in which Figure I shows my shoe-stretcher with one of the halves partially removed. Fig. II shows a top view of my shoe-stretcher.

In the drawings—

20 1 represents the body of my shoe stretcher which similarly to all other stretchers is divided longitudinally through the middle into two parts 2 and 3. Parts 2 and 3 each have an aperture 3 and 4 respectively into 25 each of which loosely fits ends 5 and 6 of a block 7. Through a threaded aperture in block 7 passes a threaded rod 8 which is hinged at 9 to a handle 10. Loosely mounted on the opposite end of rod 8 30 is a suitably shaped sliding block 11 which slides in shallow grooves 12 in each of the parts 2 and 3. The front end of block 11 is cone-shaped and the grooves shallow enough so that when said block 11 is moved 35 forward by screw rod 8 the front or toe parts 2 and 3 will spread apart. Mounted above a similar slanting part 13 on block 11 is member 14 which has a projection 15 which engages 13 as 11 moves forward, thus 40 pushing member 14 upwardly. Parts 2 and 3 are loosely connected by means of a plate 16 which has an aperture 17. Through this aperture 17 and into the cutout parts 18 in 2 and 3 passes a bar 19 which has 45 fastened to its right end the heel part 20 as shown. Bar 19 has a plurality of teeth 21 on its side. On the lefthand end of bar 19 is fastened a washer 22. Between washer 22 and plate 17 on bar 19 is compressed a 50 spiral spring 23 which tends to keep the heel 20 close to or against the body 1. The washer 22 is in such position that when block 11 is moved to the right by means of screw 8 it will engage said washer and 55 push bar 19 out to the right. As this bar 19 is pushed out as above described a pawl 24

pivotaly connected to block 7 by means of a pin 25 engages with each of the teeth 21 and thus holds the heel portion 20 from springing back toward the body 1. Merely releasing the pawl 24 which is held into the tooth space by a spring 26 fastened to block 7 allows the heel to spring back again to its position to the left toward the body 1. It will thus be seen that by means of block 60 11 and bar 19 the shoe can be stretched lengthwise and the stretcher locked and block 11 moved back to the left and spread sidewise by the means previously above described.

When the shoe has been stretched lengthwise as above mentioned, merely releasing the pawl 24 as previously described brings the heel back against the body 1 and allows the stretcher to be taken out.

70 It is evident that by means of buttons or special shaped members 14 put on any part of the body 1 special parts of the shoe can be formed to meet any peculiar conditions necessary in shaping the shoe to meet the 80 shape of the feet.

It will be seen from the above description that it is possible with my shoe stretcher to spread the toes of shoes, to lengthen shoes and to give them special shapes, and that it 85 is done by a simple and practical means.

It will be understood, of course, that while I have here shown one form of my invention I do not wish to limit myself to the exact form shown, but wish to have it taken 90 in a sense illustrative of any and all forms of my invention coming fairly within the scope of my claims.

I claim—

1. In a shoe stretcher, a body divided longitudinally into two parts, a plate having an aperture loosely mounted on the rear of said body parts, a rod passing through said aperture, teeth formed on said rod, a heel portion mounted on one end of said rod, 95 with resilient means on the other end for keeping said heel part normally against said body parts, mechanical means for spreading the forward end of said body parts and for moving said heel part away from said body 100 parts, and mechanism for locking said heel part at a predetermined point.

2. In a shoe stretcher, a body divided longitudinally into two parts, a plate having an aperture loosely mounted on the rear of 110 said body parts, a rod passing through said aperture, teeth formed on said rod, a heel

- portion mounted on one end of said rod, with resilient means on the other end for keeping said heel part normally against said body parts, mechanical means for spreading the forward end of said body parts and for moving said heel part away from said body parts, with mechanism for locking said heel part at a predetermined point, said means comprising a nut block mounted in said body parts and a threaded rod through said nut block so that its forward motion beyond a predetermined point spreads said body parts, and its backward motion beyond said point moves said heel part and a pawl pivotally connected to said nut block which engages the teeth in said rod.
3. In a shoe stretcher, a body divided longitudinally into two parts, a plate having an aperture loosely mounted on the rear of said body parts, a rod passing through said aperture, teeth formed on said rod, a heel portion mounted on one end of said rod,

with resilient means on the other end of said bar for keeping said heel part normally against said body part, a block having a 25 threaded aperture mounted in said body parts, a threaded rod passing through the threaded aperture and means journally mounted on said rod and slidably mounted in said body parts so that when the threaded 30 rod is rotated and moved forwardly the toe parts of said body parts will be spread apart, and when rotated in reverse direction to move it beyond a predetermined point the heel part will be moved away from said 35 body parts, and mechanism pivotally mounted on said lock for engaging teeth on said rod retaining said heel in its rear position when the threaded rod is moved forward to spread the said body parts.

WALTER HOLUB.
